UNITED STATES PATENT OFFICE.

PATRICK J. BROWN, OF CLEVELAND, OHIO.

HOT-BLAST STOVE.

1,140,872.

Specification of Letters Patent.

Patented May 25, 1915.

Application filed March 20, 1913. Serial No. 755,632.

To all whom it may concern:

Be it known that I, PATRICK J. BROWN, a citizen of the United States, residing at Cleveland, in the county of Cuyahoga and State of Ohio, have invented certain new and useful Improvements in Hot-Blast Stoves, of which the following is a specification.

This invention comprises an improved generative furnace of the type more commonly known in blast furnace practice as a hot blast stove, all substantially as herein shown and described and more particularly pointed out in the claims.

In lieu of following the general practice of using special forms of brick, my aim is to construct a very efficient hot blast stove at less cost than at present by using a common rectangular form of brick which is kept in stock by many dealers and therefore immediately obtainable on demand.

My object also is to construct a stove which will be easy and economical to repair; in which the checker walls are thoroughly bonded together; and in which the checker walls are bonded to the outer walls in such a manner that the checker walls may be taken down and replaced without weakening the outer walls and without removal of the shell or bridge walls. The checker walls are also supported by arches and piers particularly arranged to uniformly distribute the flow of gases and to afford easy access for cleaning.

A further object is to construct the combustion chamber walls with independently removable courses of brick at different elevations whereby burnt-out portions thereof may be replaced without disturbing adjacent courses of brick.

In the accompanying drawings, Figure 1 is a central vertical section on a reduced scale of the top, bottom and an intermediate portion of my improved hot blast stove. Fig. 2 is a perspective view of a part of the checker walls. Fig. 3 is a vertical section through the base part of the stove on line 3—3, Fig. 1. Fig. 4 is a cross section of the stove on irregular line 2—2, Fig. 3, showing one-half of the stove on a line 50 through one course of checker bricks and the other half through the subjacent course of bricks; and Fig. 5 is a cross section of the stove on the same irregular line but with the checker walls removed. Fig. 6 is a cross section on the irregular line 6—6, Fig. 3,

showing the girders and arches in plan at one side of the median line and the piers in cross section at the other side.

The furnace or stove in detail comprises a circular jacket or outer wall 2 braced internally by a curved bridge wall 3 which divides the interior of the stove vertically into a combustion chamber 4 and a heating chamber 5, the latter being subdivided by checker walls 6 to provide a large number 65 of vertical flues and the greatest possible heating surface obtainable within the circumscribed area. The top of the stove is inclosed by a dome 7, and the outer wall is inclosed by a metal shell 8, as usual. 70 Checker walls 6 rest on short girders 9 and beveled arches 10 which are supported by rectangular piers 11. A hot blast duct 12 communicates with the bottom of combustion chamber 4, and this chamber also has 75 other communicating passages extending through its outer wall, passage 14 being adapted for use with a gas burner (not shown) and passage 15 providing an air inlet for chamber 4. The base of the stove 80 beneath heating chamber 5 is also provided with a series of openings 16 radially thereof to give access to the interior in cleaning out and removing dust accumulations. A rear opening 17 provides a cold blast connection, 85 and the openings 18 and 19 are used for chimney valve and air relief connections. The piers 11 are arranged in parallel rows with intersecting galleries 12' therebetween 90 through which the gases are uniformly distributed and whereby convenient access to every inside base portion of the stove may be had by way of the radial openings in the outer wall 2. The arches 10 extend from the bridge wall 3 to the rear of the stove and 95 the girders 9 are arranged at right angles thereto and the top of each arch is beveled at one side (Fig. 3) to widen the communicating space with the checker flues.

The checker walls are built of 6" x 3" x 9" 100 fire brick laid on the 3" x 9" face and bonded as follows: Thus assuming one course of checker bricks to include all the bricks laid in the same horizontal plane over the entire cross sectional area of the the heating chamber 5, this course is built up by bricks *a* laid end to end in parallel rows at right angles to the median line *m*—*m*, Fig. 4, of the stove and by spacing bricks *b* laid in parallel lines at right angles to the rows of bricks *a*. The 105 110 115

ends of bricks *a* abut against one another, whereas the ends of bricks *b* abut against the side faces of bricks *a* in every instance. The superposed course of bricks differs however 5 from the foregoing (see upper half of Fig. 4) in that the bricks *a* which abut end to end are laid in rows parallel with the median line *m*—*m* and therefore at right angles to the subjacent rows of bricks *a*, and which 10 also places the spacing bricks *b* in the superposed course at right angles to the rows of spacing bricks *b* in the said subjacent course. This bonds the bricks at right angles in alternative courses, the spacing bricks *b* as 15 superposed being at right angles and staggered in respect to one another. The result is a complete tie or bond between all the checker brick to effectively resist vibration and prevent breakage and the filling up of 20 the flues with broken pieces of brick. The checker brick is also bonded or tied with the outer wall 2 and the bridge wall 3 without cutting or fitting or the requirement of special forms of brick and the particular con- 25 struction of the outer wall 2 which permits the result to be accomplished is as follows: The bricks for the outer wall are the same size and kind as the checker brick, but are laid for the most part on the 6" x 9" faces 30 instead of the 3" edge thereof. This provides two layers of bricks in the outer wall to each layer of checker brick, and that particular portion of the outer wall which in- 35 closes heating chamber 5 has the bricks there- of laid in straight rows parallel with the rows of the bonding bricks *a* of the checker walls. In fact outer wall 2 also includes 3x6x9" bricks *a'* laid on their 3" edge as extensions of the rows of the checker bricks 40 *a*, and by referring to Fig. 4 which shows two superposed courses of bricks, it will be seen that the bricks *a'* which correspond to one course of the checker walls are laid at right angles to the bricks *a* which correspond 45 to the other higher or lower course. The filler bricks *b'* in wall 2 may be either 3x6x9" bricks laid on their 6" face or 3x4½x9" laid on their 4½" face.

The outer surface of wall 2 is rounded, 50 but the inner part is built up to provide pilasters 20 extending the full length of the stove, whereby the circular wall is greatly strengthened and made self-sustaining. The right-angled faces of the pilasters embody 55 the bonding bricks *a* and *a'*, whereby the checker walls are firmly tied to the outer wall 2 but without special cutting or fitting. Stated in another way, the flat faces of the pilasters are at right angles to each other 60 and flush with the checker walls and have the bonding bricks *a* and *a'* inset in said faces. The advantage of the pilastered wall and checker wall constructed as described is manifold; first, that no special form of brick 65 is required, ordinary stock brick being all

that is necessary to construct or repair the stove; second, that the checker walls are firmly bonded together; third, that the checker walls can be removed and replaced without tearing down or weakening the 70 outer wall 2; and fourth, that new checker walls may be built up with as strong an interlocking union with the original wall as formerly and without bracing the walls.

In view of the curvature of bridge wall 3, 75 the outer wall 2 is built in to conform thereto where joined therewith, and the built-in portions 21 and 22 may also be regarded as pilasters for the bridge wall and with the same bonding advantages for the checker 80 walls as in the other instance. Curved bridge wall 3, and the segmental portion of wall 2 which forms the outer wall of the combustion chamber 4, are built up by an inner and outer lining of bricks laid on radial lines. 85 The thickness of bridge wall 3 is approximately twenty-two or twenty-three inches for a height of twenty feet, and it is the lining of this part of the bridge wall and the opposite chamber wall that is directly ex- 90 posed to the hottest blasts and therefore more likely to burn out, particularly the portions marked 24 and 25. Consequently these walls are built of standard brick 9" x 6" x 3" for five courses, more or less, and 95 every sixth course is made of header bricks 26 approximately 13½ inches in length which are bonded with the bricks forming the outer lining. This construction permits convenient removal and replacement of the inner lining between any two courses of header 100 bricks 26 without injury to the rest of the wall and without risk to workmen in making repairs.

The reference numeral *a*² denotes the ex- 105 tension of the right angled walls *a* and *b* into the outer wall of the stove, and the reference numeral *b*² the bricks or units from which the outer wall is built.

What I claim is:

1. A hot blast stove of circular form having an outer wall and a segmental bridge wall of brick to provide combustion and heating chambers, said heating chamber having checker walls of rectangular bricks having a width exactly double their thickness laid at right angles to each other on their narrow faces and located between said outer wall and said bridge wall, and the outer wall built up of rectangular bricks having a thickness of equal thickness to said checker brick laid on their wide faces in double courses in bonded relations with each other and the checker bricks and having the lines of checker bricks extending into the same. 115

2. In a hot blast stove, checker walls formed of rectangular 9 inch x 6 inch x 3 inch brick laid on their narrow edge in right angled rows in bonding and spaced relations to provide vertical flues with vertical walls as thin 120

as one brick, and an outer wall comprising superposed rectangular bricks 9 inch x 6 inch x 3 inch laid at right angles on their narrow edges as extensions of said checker walls,
5 and double layers of rectangular filler bricks of 3 inch thickness laid between said extension of each course of checker bricks.

In testimony whereof I affix my signature in presence of two witnesses.

PATRICK J. BROWN.
